UNITED STATES PATENT OFFICE.

MANLEY W. CLUXTON, OF CHICAGO, ILLINOIS.

METAL SHEET-PILING.

No. 878,773.

Specification of Letters Patent.

Patented Feb. 11, 1908.

Application filed September 10, 1907. Serial No. 392,161.

To all whom it may concern:

Be it known that I, MANLEY W. CLUXTON, a citizen of the United States, and a resident of Chicago, in the county of Cook and State 5 of Illinois, have invented certain new and useful Improvements in Metal Sheet-Piling; and I do hereby declare that the following is a full, clear, and exact description thereof, reference being had to the accompanying 10 drawings, and to the letters of reference marked thereon, which form a part of this specification.

This invention relates to improvements in metal sheet piling of that character in which 15 the sections or units of the piling are made of commercial rolled shapes or bars, such as I-beams and the like.

The object of the invention is to provide, in combination with simple forms of rolled 20 metal bars, devices for affording a guiding connection between the sections or units as they are driven into the ground, arranged to guide each section as it is being driven from a previously driven section in a generally 25 similar manner to interlocking sheet piling.

The present invention is adapted to sheet piling designed for lighter work, such as may be economically used in construction of 30 sewers, for the reinforcement of concrete structures, as dikes, foundations and the like, where special regard need not be had to water-tight joints between the several sections and where conditions do not warrant 35 the use of the more expensive sheet piling of the interlocking type.

The invention consists in the matters hereinafter set forth and more particularly pointed out in the appended claims.

In the drawings:—Figure 1 is a partial side 40 view of a retaining wall made of sheet piling constructed in accordance with my invention, showing the means for guiding the piling sections as they are driven and for retaining them laterally in position after they 45 are in place. Fig. 2 is a perspective view of one section of the sheet piling. Figs. 3 and 4 are detail sections taken on lines 3—3 and 4—4, respectively, of Fig. 1. Fig. 5 is a perspective view of one of the guiding and retaining clips. Fig. 6 is a horizontal plan view of the segment of a circular wall made 50 of sheet piling embodying my invention.

As shown in the drawings, 10, 10 designate the sections or units of the sheet piling 55 which, as herein shown, have the form of

commercial rolled I-beams, said beams each consisting of a central web 11 and oppositely disposed marginal flanges 12, 12. Said sections are adapted to be driven into the ground with the flat sides of the flanges 12 bearing one against the other to form a continuous wall. 13, 13 designate guiding clips which are secured to the webs of said sections and are adapted to project laterally therefrom over the marginal flanges 12 for engagement with the like flanges of an adjacent section. Said clips comprise, in each instance, two members and, when employed in connection with I-beam sections, consist each of a shank portion 14 which is adapted to fit flat against the side face of the web of the section to which it is attached and a hooked end 15 made of a shape to extend over and beyond the marginal flange 12 of the section to which it is attached and to fit closely the inner face of said flange. The said hook portions of said clips are made of such dimension as to closely embrace the meeting flanges of adjacent sections, as more clearly shown in Figs. 3 and 4.

The guiding and retaining clips are fixed to the sections by means of bolts or rivets 16, 16 extending through the shanks of the clips and through the webs of the piling sections over which the said shanks fit. Two of said guiding and retaining clips are applied to each of said sections, one adjacent to the bottom thereof and the other adjacent to the top. The rivets or bolts 16 by which the upper clips are attached to the upper ends of said sections may extend through the usual draw opening 17 punched in the webs of said sections to afford means for withdrawing the sections from the earth when their services are no longer required. Inasmuch as the bases of the hooks bear flat against the inner faces of the flanges 12 of the sections, the attachment of said clips to the sections by a single bolt or rivet in this manner will usually be all the fastening means required.

In the use of the retaining and guiding clips, one of said clips, comprising the two members described, is attached to the lower end of the section next to be driven and projects laterally therefrom for engagement with the flanges 12 of a section which has previously been driven. After the section has been driven into the ground a short distance, a second clip is attached to the upper end of the previously driven section with its

hook portions engaged in interlocking connection with the abutting flanges of the two adjacent sections. It will be observed that the said upper clips are attached to the upper 5 ends of the said sections at the level of said upper end of the section after they are driven, which is a position convenient and accessible for the ready attachment of said clips. After the upper clip has been attached to the 10 upper end of a previously driven section in the manner indicated at the right hand side of Fig. 1, the upper and lower clips, attached one to the driven section and one to the section being driven, constitute guides for holding 15 the sections in proper relative position to each other as the last section is driven into place, the guiding engagement between said sections increasing in distance between each other as the driving of the last section progresses. 20 The lower ends of the sections need not be prepared for driving by sharpening or otherwise, inasmuch as the material is so thin as to afford a good driving point. It will be observed that the clips are attached 25 to the webs of the sections above and below the ends thereof, thus leaving the lower ends of the sections free from any obstruction or hindrance to their free driving into the earth. The said clips constitute means, not only for 30 guiding each section as it is driven into place, but also retaining means for holding the sections together after they are driven, so as to constitute an unbroken continuous wall made up from the separately driven sections. 35 The connection between the sections are of such strength as to constitute a strong retaining or lining wall for an excavation in the earth where the earth is of such character as to impose only a moderate stress 40 against the lining thus formed.

In Fig. 6 I have shown my invention as applied to the construction of a circular wall. In this construction the webs of the sections 45 are transversely curved concentric to the center of said wall and the marginal flanges of said sections are disposed radially to the center of the wall. The construction shown in said Fig. 6 is designed to form the lining wall of a shaft which is excavated in the earth, the earth being removed from the space surrounded by said piling sections after the latter have been driven. The engagement of the flanges of the sections in the circular form of wall adds 50 to the strength thereof to resist inward collapse by reason of the earthen walls.

The construction of a lining or reinforcing structure made in accordance with my invention is exceedingly simple and inexpensive. 60 The clips afford means for accurately guiding the sections while being driven and holding them in close engagement with each other to prevent the leaking of the earth of the earthen walls between adjacent sections

as reliably as with interlocking sheet piling 65 wherein the guiding engagement between adjacent sections extend from end to end of the piling sections. As before stated the said piling may be used as the lining or retaining wall of an excavation, the piling being first driven into the earth and the earth removed from the area surrounded by the sheet piling wall. The piling may also be driven into the earth to constitute a reinforcement or anchorage for a concrete 75 structure, as a dike, the foundation of buildings and the like. The retaining and guiding devices herein shown may be applied to sections made of other form than that illustrated and will be modified as to shape to 80 correspond to different forms of piling sections.

I claim as my invention:—

1. In metal sheet piling, the combination with adjacent sections or units composed of 85 flat webs and marginal flanges, the flanges of adjacent units bearing flat one upon the other, of vertically narrow retaining and guiding clips attached to the webs of said sections at the upper and lower ends thereof, 90 the clips of each section being formed to provide hooks that extend over and engage the flanges thereof and the flanges of adjacent sections.

2. In metal sheet piling, the combination 95 with adjacent sections or units comprising flat webs and marginal flanges, the flanges of adjacent sections fitting flat one upon the other, of guiding and retaining clips at the upper and lower ends of said sections comprising narrow shanks which are fitted flat against and attached to the webs of the sections and hook portions which extend laterally over the webs of the sections to which they are attached and in interlocking engagement with the flanges of adjacent sections. 105

3. In metal sheet piling, the combination with adjacent sections or units composed of flat webs and marginal flanges, the flanges of adjacent units bearing flat one upon the 110 other, of vertically narrow retaining and guiding clips attached to the webs of said sections at the upper and lower ends thereof, the clips of each section being formed to provide hooks that extend over and engage the flanges thereof and the flanges of adjacent sections, the clips associated with two adjacent sections being attached, one to the web of one section near the bottom thereof and the other to the web of the other section near 115 the top thereof.

4. In metal sheet piling, the combination with adjacent sections formed of I-beams and arranged with their flanges fitting flat together, of guiding and retaining clips comprising narrow shank portions fitting flat upon and attached to the webs of said sections, and hook portions extending over the 125

marginal flanges thereof and into interlocking engagement with the marginal flanges of adjacent sections, the clips of two adjacent sections being attached one to one section 5 thereof near the bottom thereof and the other to the other adjacent section near the top thereof.

In testimony, that I claim the foregoing as my invention I affix my signature in the

presence of witnesses, this 5th day of September A. D. 1907.
